INVENTOR

William Gorman

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,533, dated June 8, 1869.

DESIGN FOR A HINGE.

The Schedule referred to in these Letters Patent and making part of the same.

To all whom it may concern:

Be it known that I, WILLIAM GORMAN, of New Britain, in the county of Hartford, and State of Connecticut, have originated and designed a new Design for a Door-Hinge; and I do hereby declare that the following is a full, clear, and exact description thereof, reference being had to the accompanying drawings, making a part of this specification.

It is customary, for the purpose of concealing the heads of the screws, to cover the faces of the better class of door-hinges with a plate, *aa*, shown in section at Figure 2.

The design, herein described, is intended to be employed upon such plate, so used to cover the face of the hinge, as seen at Figure 1, and a corresponding

design is intended to be cast upon the back of the hinge, as seen at Figure 3.

The edge of the plates covering the leaves of the hinge, is surrounded by a band, *a*, which may be raised, or otherwise, and be plain, or some architectural moulding. The central portion is occupied with a circular shield, and the remaining space filled with ornamental work, in relief, upon either a plain or "matted" ground.

What I claim as my invention, and desire to secure by Letters Patent, is—

The design for a hinge, or hinge-plate, substantially as shown in fig. 1 of the drawings.

Witnesses:

WILLIAM GORMAN.
